UNITED STATES PATENT OFFICE.

HARVEY SEGUR AND EDWARD H. DUDDY, OF CHICAGO, ILLINOIS, ASSIGNEES TO ASA B. SEGUR, DOING BUSINESS AS A. B. SEGUR & CO., OF CHICAGO, ILLINOIS.

EGG-CASE-FILLER MACHINE.

Application filed August 22, 1921. Serial No. 494,296.

To all whom it may concern:

Be it known that we, HARVEY SEGUR and EDWARD H. DUDDY, both citizens of the United States, and both residing at Chicago, in the county of Cook and State of Illinois, have invented certain new and useful Improvements in an Egg-Case-Filler Machine; and we do hereby declare the following to be a full, clear, and exact description of the invention, such as will enable others skilled in the art to which it appertains to make and use the same.

Our invention relates to machines for manufacturing the cell-cases or transversely partitioned fillers as used in crates or boxes for separating eggs, fruit or the like. Such machines as now in common use are constructed for punching the required interlocking formations on separate webs or strips of paper or cardboard, cutting the punched webs or strips to the needed lengths, automatically assembling the strips formed from the two webs so as to interlock them, and feeding the resulting assembled cell-cases to the delivery table of the machine.

Generally speaking, our invention aims to simplify and expedite the making of various important adjustments on machines of this kind and also aims to expedite the positioning and replacing of the punches and dies as used for producing the interlocking formations on the strip portions which are assembled by the machine into cell-cases. In operating machines of this general class (of which class the cell-case machine disclosed in U. S. Patent No. 622,403 to George W. Swift, Jr., is an example) it is important that the distances between the punching and shearing dies associated with each paper web or strip should be properly adjusted, so that the interlocking formations on the relatively transverse strips will be in proper position for enabling the machine to interlock the same. Even if the adjustments for this purpose are made with the desired accuracy during the initial construction of the machine, the elongation or shrinkage of the paper or cardboard due to humidity and other conditions spoils the adjustment even when the same grade thickness of paper is used. The pressure of the paper feeding rolls may also effect a further difference

in the elongation of the paper, and this effect may likewise vary with the grade and thickness of the paper used and with the atmospheric conditions.

Consequently, the effective distance between the punching arrangement for notching and slotting each set of strips and the shearing means for cutting off the same set of strips requires adjustment whenever the grades or thickness of the paper are changed, and likewise requires adjustment from time to time according to the varying atmospheric conditions. With the machines as now in common use, such as those of the type disclosed in the above mentioned patent, the making of such adjustments for the horizontally fed strip (or the one which is upwardly notched in the completed cell-case) requires a disconnecting or partial dismantling of the corresponding punch and die arrangement and also requires the making of the needed adjustment by a cut-and-try method involving a good deal of time and hence keeping the machine idle for a correspondingly long period. In one of its aspects, our invention aims to obviate this loss of time and to expedite the making of such adjustments by providing a movable mounting for the punch and die, together with simple means for adjusting the position of this punch and die without dismantling any portion of the supports for the same.

Another adjustment needed for such machines because of variations in the shrinkage or elongation of the paper is that required in connection with the strips formed from the upper web, or those which are provided with downwardly open notches for straddling the first named set of strips. To expedite this adjustment, our invention aims to provide simple and effective means for throwing the upper feed rolls into and out of engagement with the upper web of paper, and for maintaining an even pressure across this web so as to feed the same in the desired direction. It also aims to provide an adjustment for this purpose which will automatically align the feed rollers with their bearings, so as to avoid undue friction.

A further and also important adjustment as needed in a machine of this type is that required for determining the distance to which the downwardly notched strips are

pressed downwards in assembling them in interlocking relation to the upwardly notched strips. Heretofore, this has been effected partly by the action of one of the cutters when sliding past the cooperating cutter, these cutters being disposed in approximately the same plane. With such an arrangement, it has been difficult to secure just the right extent of downward pressure by the movable cutter on the strip which is to be interlocked by the action of this cutter with a series of other strips, as any shortage of this pressure would deter the interlocking formations on the relatively transverse strips from snapping into one another, while an excessive pressure would cause the movable cutter to nick or indent the strips. Furthermore, with the cutter knives disposed in approximately the same plane, the resistance of the paper to the cutting tends to slide the cutters out of adjustment, thereby necessitating frequent attention to this portion of the machine. Our invention aims to overcome all of these objections, partly by mounting the cooperating cutters at a decided angularity with respect to each other, partly by affording an adjustable support for the rear edge of the movable cutter which will positively prevent the movable cutter from being slid out of position by resistance to the cutting, and partly by providing a simple and easily effected means for varying the extent of movement of the movable cutter and thereby adjusting the extent to which this effects the movement of the paper strip sheared off by it.

Still another difficulty encountered with machines of this class and one which has led to a great waste of time and labor has been that of attaching and replacing the punches and dies, and particularly those associated with the upper or downwardly fed paper portions. Heretofore, a considerable dismantling of the adjacent portions of the machine has been required to permit of attaching or removing any punch or die, thereby requiring a good deal of labor and keeping the machine out of commission for undesirably long periods of time. Our invention aims to obviate these difficulties by providing punch and die holders so arranged that new punches and dies can easily and quickly be attached to the same, or detached therefrom, without detaching any other portions of the machine, and aims to accomplish this purpose while still insuring a firm supporting and a proper positioning of the punches and dies.

Still further and more detailed objects will appear from the following specification and from the accompanying drawings, in which—

Fig. 1 is a central and longitudinal section through the forward portion of a ma-

chine embodying our invention, with the extreme forward end of the delivery table broken away.

Fig. 2 is an enlarged plan view of the drop punch head of the machine, taken from the correspondingly numbered line in Fig. 1 but with the runway support removed.

Fig. 3 is a fragmentary rear elevation of the same drop punch and die head.

Fig. 4 is a side elevation of the same punch and die head, taken from the side of the machine opposite to that from which Fig. 1 is viewed.

Fig. 5 is an enlarged vertical section through the knife head and punch head used for punching and shearing the upper paper, taken along the correspondingly numbered line of Fig. 6 and showing the knives as just starting the cutting.

Fig. 6 is a plan view of the same knife head and punch head.

Fig. 7 is a fragmentary vertical section taken along the correspondingly numbered line in Fig. 6 and showing the swivel connection of the adjustable link which oscillates the movable knife head.

Fig. 8 is a fragmentary horizontal section taken along the correspondingly numbered line in Fig. 5 and showing the fastening of the stationary knife.

Fig. 9 is an enlarged horizontal section through the bearings for the ends of the rolls which feed the upper paper, taken along the correspondingly numbered lines of Fig. 1 and Fig. 10.

Fig. 10 is a vertical section of the same parts, taken along the correspondingly numbered line of Fig. 9.

Fig. 11 is an end elevation of the parts shown in Fig. 10.

Figs. 12 and 13 are horizontal and vertical sections respectively corresponding to Figs. 9 and 10 but showing an alternative embodiment of the arrangement of our invention for adjusting the roller bearings.

Fig. 14 is an end view of the same parts as Figs. 12 and 13, taken from the right hand side of Fig. 13.

Fig. 15 is a fragmentary view of one of the upper or downwardly fed paper strip portions, showing the notches as punched in the same.

Fig. 16 is a fragmentary elevation of one of the lower paper strip portions, showing the upwardly open notches and the tongue-engaging perforations in the same, with a dotted line showing the location of the shear cut.

Fig. 17 is a perspective view of an assembled egg-case or cell case filler as made by employing our invention.

While various features of our invention may be employed with substantially equal facility on a considerable variety of machines, they are particularly suited for ma-

chines of the general class shown in the cited Swift Patent No. 622403 and are therefore illustrated in such a connection in the accompanying drawings. In these drawings,

5 the cell-case machine includes a frame 1 supporting a table 2 over which lower strips of paper 3 are fed by power driven rollers 4 towards a delivery table 5 at the forward end of the machine, each strip being twisted 10 into a vertically edgewise position by passing between a pair of closely spaced rollers 6 before it reaches the shear 7 which cuts the strip to the desired length. The paper strips 3 also pass respectively between the 15 die head 8 and the punch head 9 of Figs. 2, 3 and 4, which heads carry punches 10 and 11 and corresponding cooperating dies for forming the edge slots 12 and the T-shaped perforations 13 in the paper strips 3, the 20 resulting formations being shown in Fig. 16.

The frame 1 of the machine also indirectly supports a runway 14 disposed at a considerable distance above the table 2 and guiding an upper web 15 of paper to feed 25 rollers 16 and 17, which rollers feed this outward past a horizontally movable punch head 18, and a corresponding stationary die head 19, as shown in Fig. 1, and then past the stationary cutter 20. While being thus 30 fed, the web 15 is engaged at intervals by punches 21 secured to the punch head 18 and cooperating with corresponding dies 22 carried by the die head 19, so as to notch the web 15 substantially after the manner shown 35 in Fig. 15. That is to say, this web is punched along one edge to provide downwardly open notches 23 spaced from each other by the distance at which the strips 3 are to be spaced apart in the finished cell- 40 case, each of these notches having intermediate its depth a tongue 24 adapted to project through one of the T-shaped perforations 13 in a companion strip 3 so as to interlock this strip with the web 15. After 45 being thus notched, the web 15 is fed downward into the position shown in Fig. 5, with the notches 23 and 12 in the two paper members respectively straddling the companion paper members and with the free edge of the 50 web 3 disposed at some distance above the table 5. Then the movable knife 25 is swung past the path of the web 15 and in close shearing relation to the cutting edge of the stationary cutter 20 so as to shear off an end 55 of the web 15 corresponding in length to the height of the proposed cell-case, for which purpose the movable cutter 25 is desirably mounted on a rocking lever 26 which is pivoted on a rock-shaft 27 disposed below and 60 forwardly of the cutting edge of the stationary knife. This rocking lever is connected by an adjustable link 28 and a swivel fork 29 to the punch head 18 which is slidably mounted on a stationary guide 30 (as 65 shown in Fig. 1) and which is continuously

oscillated by a rod 31 connecting an eccentric strap 32 with an eccentric fastened to the continuously rotating drive shaft 33 of the machine.

Thus arranged, it will be seen from Fig. 5 70 that a movement of the rocking lever 26 towards the right in that figure will cause the movable cutter 25 to shear off the lower end of the web 15, and that the bevel of the cutting edge on the cutter 25 will act as a cam 75 for forcing the severed end of the web 15 downwards or into effective straddling relation to the transversely disposed strap 3. Moreover, the inclination of the rock shaft 26 presents the cutter 25 at a downward inclination to the web 15, so that this cutter is inclined in a direction tending to advance the web 15; hence the movement of the cutter cooperates with the bevel of its cutting edge in forcing the severed web end downwards. By suitably adjusting the extent of movement to which the extreme cutting edge of the knife or cutter 25 passes beyond the plane along which the web 15 is fed downward, we can therefore insure an adequate 80 interlocking of the downwardly fed web with the horizontally fed strips 3. To accomplish this adjustment and to avoid an excessive movement which might cause the cutter 25 to nick or indent the constituent 85 elements of the resulting cell-case, we desirably thread the link 28 and clamp it to the swivel member 29 by nuts 63 and lock nuts 64, it being understood that link 28 extends through an unthreaded bore in the said 90 swivel member. Thus arranged, it will be evident from Fig. 5 that by loosening the nuts 63 and 64 we can readily vary the effective length of the link 28 so as to adjust the distance for which the cutting edge of the 95 cutter 25 is moved beyond the path of the web 15 during the cutting movement of this cutter. By disposing the stationary knife 20 in a downward inclination to the web and oblique to the movable cutter, we avoid direct thrusts tending to shift the stationary cutter from its position, hence fastening bolts 61 extending through slots in this cutter after the manner shown in Figs. 5 and 8 suffice for securing this in position while 100 also permitting it to be shifted to allow for wear on its edge. However, the resistance to the cutting will tend to slide the similarly bolted movable cutter 25 backwards (or to 105 the left in Fig. 5) hence we desirably provide push screws 62 engaging the back of this cutter for resisting this thrust.

To facilitate the attaching, removing and replacing of the punches and dies, we do not bolt these direct to the punch heads or die heads after the manner heretofore customary, but first attach holders equipped for the convenient or speedy attaching or removal of the punch and die parts. Thus Fig. 5 shows the punch head 18 as having 110

a punch holder 65 secured to the same by cap screws 66. This holder 65 is undercut along the face directed towards the punch head 19 to afford a mortise formation for receiving the dovetailed rear end 34 of the punch 21, and the holder 65 has threaded into it set screws 35 for engaging the corresponding upper bevel face of the same dovetail base, which screws desirably extend substantially parallel to the back of the panel. By loosening the set screws 35, the punch 21 (including this dovetail base 34) can readily be removed and a substitute punch can easily be fastened in position by correspondingly slipping it into place and tightening the set screws 35. The die head 19 is provided with a correspondingly mortised holder 36 carrying similarly disposed set screws 37 for the same general purpose, so that the dies 22 can likewise be attached or detached very quickly and without dismantling or detaching any portion of the machine.

A similarly constructed punch holder 38 is desirably also mounted on the drop punch head 9 as shown in Fig. 1 for detachably holding the punches which cut the notches and T-shaped perforations in the horizontally fed strips 3. To adjust these drop punches 10—11 and the corresponding dies in proper position with respect to the vertical plane in which the web 15 is fed downwardly, we support both the drop punch end 9 and the drop die head 8 on a carrier 40 which slides upon guide ribs 41 on the frame of the machine, as shown in Figs. 3 and 4, and which can be clamped in adjusted position by means of bolts 42. Then we connect the frame 1 with the slidable carrier 40 by a bolt 43 fastened to the said frame and extending through an ear 44 on the carrier, so that the carrier may be moved backwards or forwards by adjusting nuts 45 threaded upon the bolt 43 at opposite sides of the ear 44 as shown in Figs. 1 and 4. By manipulating the nuts 45 we can readily shift the entire carrier backward or forward of the machine, so as to adjust the distance of the drop punch head from the plane in which the web 15 is fed downwardly and from the shear 7 which is arranged in the usual manner for shearing the strip 3 to the proper length. In practice, the amount of adjustment needed for this purpose owing to variations in the grade of paper, or stretch or elongation of the same due to atmospheric conditions, or on account of varying elongating of the paper by the pressure of the feed rolls 4 is not so much as to interfere with our using the carrier 40 also as one of the supports for the runway 14, so that we desirably equip a support 46 on the top of the carrier 40 as shown in Fig. 1 for supporting one end of the runway.

Owing to the relatively large width of the

upper web 15 of the paper as compared with the strips 3, it is important that this should be fed squarely downward by the upper feeding rolls 16 and 17, as a variation in the feeding pressure between the two ends of the rolls would shift the downwardly fed free end of the web sideways of the machine and hence would bring the slots 23 out of alignment with the webs 3 which these slots are to straddle. To secure this even distribution of the pressure without undue friction on the bearings and to permit a ready separation of the rolls 16 and 17 when the feeding is to be interrupted, we desirably mount the bearings for one of these rolls in stationary position and provide simple means for simultaneously moving the bearings for the companion roll towards or away from the aforesaid bearings, and for latching them in any desired position. For this purpose, Figs. 9 to 11 inclusive show the bearings 47 and 48 associated respectively with the said two rolls as both seated in a slideway on a side portion of the frame 67 of the machine, the forward bearing 47 being locked in position by engaging a wall 49 in front of this bearing and by a pin 50 inserted behind this bearing. The companion bearing 48 for the rear roll is left free to slide between the said side frame portion 67 and a cap 51 bolted to the latter and may be connected by a link 52 to an eccentric 53 on an eccentric shaft 54 extending transversely of the machine and adapted to be rocked by a handled lever 55, it being understood that the arrangement is the same at both sides of the machine and that the single lever 55 will serve for simultaneously moving the bearings supporting both ends of the rolls 17. The eccentric shaft 54 is pivoted in a bearing block 56 which is also slidably mounted as shown in Fig. 10 and is adjusted in position by a set screw 57 locked by a nut 58. By loosening the lock nut 58, we can vary the distance between the eccentric shaft and the axis of the stationary roller 16, thereby correspondingly varying the closeness of approach of the two rollers to each other when the lever 55 is in the normal position in which the rolls engage the paper web between them. However, by throwing the eccentric to its diametrically opposite position, we can separate the rollers to such an extent that they will not grip the web, so that the feeding will be interrupted until the lever 55 is returned to its former position. The arrangement thus disclosed therefore affords a simple adjustment of the rollers to match different thicknesses of paper while still permitting the rolls to be thrown instantly into or out of feeding relation to the web without stopping the machine.

However, while we have illustrated and described both our upper feed roller adjustment and other features of our machine in

highly desirable embodiments, we do not wish to be limited to these, as it will be obvious that the details of construction and arrangement may be varied in many respects 5 without departing from the spirit of our invention or from the appended claims. For example, Figs. 12 to 14 inclusive show another form of feed roller adjustment also accomplishing the same purposes, namely 10 one employing a compression spring 59 between the bearings 47 and 48 for continuously tending to separate these bearings, and employing a thrust bar 60 interposed directly between movable bearing 48 and the 15 eccentric 53 on the eccentric shaft 54 for resisting the thrust of the spring 59. With this arrangement it will readily be seen from Fig. 13 that by adjusting the normally locked screw 57, we can readily vary the 20 position of the bar block 56 in which the eccentric shaft is journaled, thereby causing the thrust bar 60 to cooperate with the spring 59 in maintaining the desired spaced relation between the bearings for the two 25 feed rolls. With either of these eccentric-operated roll spacing arrangements we desirably dispose each thrust member (namely the link 52 or the thrust bar 60 so that it engages the adjacent movable bearing 30 dially of the latter, thereby permitting this bearing to rock about the thrust member in automatically alining itself with the roll journaled upon it).

So also, we do not wish to be limited to the 35 inclusion of all of the above described features in connection with each other, it being evident that they might be employed singly or in other combinations if desired, and it also being evident that the application of 40 the various features of our invention is by no means limited to the particular type of machine pictured and described by us.

We claim as our invention:

1. In a cell-case machine, a web-severing 45 cutter, a punch and die arranged for punching the strip prior to the cutting, and a unitary and movable mounting for the punch and die whereby the punch and die may be adjusted in distance from the severing cutter without disturbing their relative positions and without disturbing any other portions of the machine.

2. In a cell-case machine, a frame, a strip-severing cutter operating in a fixed plane 55 transverse of the frame, a carrier slidably mounted on the frame back of the cutter, means upon the carrier for punching the strip, and means for moving the carrier toward or from the cutter to adjust the 60 position of the punching means with respect to the cutter.

3. In a cell-case machine, a frame, upper and lower means for respectively feeding 65 two supplies of paper, a carrier slidably upon the frame, punching means mounted on

the carrier and arranged for punching the lower supply of paper, and means partly supported by the carrier for guiding the upper supply of paper to the means for feeding the latter.

4. In a cell-case machine, strip-severing means comprising a pair of relatively movable cutters disposed in planes oblique to each other and to the face of the strip, the said cutters extending toward each other in 70 the general direction in which the strip severed by them is fed.

5. In a cell-case machine, strip-severing means comprising a pair of relatively movable cutters disposed in planes oblique to each other and to the face of the strip, the beveled cutting edge of one cutter affording a cam action for imparting an advancing movement to the strip portion sheared off 75 by the cutters.

6. In a cell-case machine, cooperating strip-severing means comprising a pair of cutters disposed in planes oblique to each other and to the face of the strip, and means for moving one of the cutters with respect to the other to effect the cutting, the direction of movement being such that the moving cutter imparts an advancing movement 80 to the strip portion sheared off by the cutters.

7. In a cell-case machine, means for feeding a web of paper, a stationary cutter disposed at an acute angle to the web and presenting its cutting edge in the general direction towards which the web is fed, and a movable cutter disposed for cooperating with the said edge in shearing the web and inclined in the same general direction towards the web but at a less acute angle.

8. In a cell-case machine, means for feeding a web of paper, a stationary cutter disposed at an acute angle to the web and presenting its cutting edge in the general direction towards which the web is fed, and a movable cutter disposed for cooperating with the said edge in shearing the web and inclined in the same general direction towards the web but at a less acute angle, and adjustable means engaging the back of movable cutter for resisting the back-thrust 95 thereon during the shearing operation.

9. In a cell-case machine, means for feeding the end of a paper strip in a predetermined plane, cooperating stationary and movable cutters normally disposed at opposite sides of the said plane and both inclined to the strip in the general direction in which the end of the strip is fed past the cutters, and means for moving one of the cutters past the other to shear the strip.

10. In a cell-case machine, means for feeding the end of a paper strip in a predetermined plane, cooperating stationary and movable cutters normally disposed at opposite sides of the said plane and both in-

3
clined to the strip in the general direction in which the end of the strip is fed past the cutters, and means for moving one of the cutters past the other to shear the strip, the 5 movable cutter having its edge beveled and disposed for imparting advancing movement to the portion severed from the strip by the cutters.

11. A cell-case machine as per claim 10, in 10 combination with means for adjusting the extent of movement of the movable cutter so as to vary the amount of advancing movement imparted to the severed strip portion.

12. In a cell-case machine, a stationary 15 cutter, means for feeding a paper strip

transversely past the cutter, a movable cutter disposed for cooperating with the stationary cutter in severing the strip and movable in a direction inclined to the other cutter, the movable cutter being inclined towards the strip in the general direction in which the strip is fed, and means for adjusting the extent to which the movable cutter is moved past the edge of the stationary cutter during its strip-severing 25 movement.

Signed at Chicago, Illinois, August, 1921.

HARVEY SEGUR.
EDWARD H. DUDDY.
